WILLIAM F. CLARK, OF BALTIMORE, MARYLAND

METHOD OF AND APPARATUS FOR STRAIGHTENING PIPES, TUBES AND SIMILAR ARTICLES

Application filed November 28, 1928. Serial No. 322,434.

In the manufacture of pipes, tubes and similar tubular and cylindrical articles, particularly those which are formed from hot metal, much time and labor are expended in straightening the articles subsequent to their discharge from the forming machine.

Where the articles, such as lengths of pipe, are formed while at a very high temperature and discharged while very hot, bends or sags frequently occur in the pipes in the interval between their issuance from the forming machine and their release from the discharge mechanism thereof onto the customary cooling rack. Such bends or sags must be removed from the pipes before they are marketable, and the straightening operation by which this is done is ordinarily performed after the pipes have cooled sufficiently to be safely handled.

This straightening operation entails an additional handling of the pipes and a consequent consumption of time and labor.

The object of my invention is to accomplish the straightening of the pipes or other articles automatically and during the customary cycle of manufacturing operations prior to their discharge from the cooling rack, thereby obviating the necessity for handling them after they have cooled and releasing the men ordinarily employed at the straightening machines for other work.

The invention consists in a method of straightening pipes, tubes and the like comprising the rolling of such articles between a fixed member and a movable member, preferably under pressure, and in the apparatus for carrying out this method.

In the accompanying drawings illustrating the invention, in the several figures of which like parts are similarly designated,

Fig. 1 is a side elevation of my straightening apparatus shown in connection with the discharge mechanism of a pipe forming machine and a fragment of one end of a cooling rack of approved form.

Fig. 2 is a fragmentary plan view of the articulated travelling band or article-carrying member.

Fig. 3 is a fragmentary plan view of the pressure-applying member.

Fig. 4 is a fragmentary end view of the machine looking at the right-hand end of Fig. 1.

Fig. 5 is an enlarged sectional detail of one of the bed-forming members and a fragment of the articulated travelling band.

Fig. 6 is an enlarged sectional detail of a modified form of surface-forming members for the pressure-applying device.

Fig. 7 is an enlarged fragmentary perspective view of the connecting bearing between the frame of the pressure-applying member and the supporting-lever members of the parallel adjusting linkage.

In Fig. 1 I have shown the discharge mechanism of a pipe forming machine which comprises a sloping table 1 adjustably mounted by means of jack-screws 2 upon suitable standards 3. Pivotedly mounted as at 4 upon the table 1 is a housing and guide member 5 within which the pipes, as they come from the forming machine, are introduced and by which they are guided. Hinged as at 6 adjacent to the lower edge of the table 1 is a bridge-piece or skid 7, the free end 8 of which rides upon the articulated travelling band or article-carrying member of the straightening apparatus, hereinafter described in detail.

In ordinary practice, the table 1 is arranged adjacent the receiving end 9 of a cooling rack of ordinary or approved form, usually consisting of a plurality of laterally spaced skids or ways 10 and travelling conveyor chains 11 provided with dogs or spurs 12 which engage the pipes throughout their length as they are discharged from the table 1 upon the rack and convey them with a rolling motion over the rack.

Inasmuch as the table 1 and its discharge mechanism and the cooling rack are of known

form and are not parts of the present invention except insofar as they contribute to its mode of operation, they are not shown and described in detail.

5 In the practice of my invention, instead of discharging the pipes from the table 1 directly upon the cooling rack, I move the cooling rack away from the table a sufficient distance to accommodate my straightening apparatus.

10 This apparatus comprises a frame-work composed, preferably, of standards 13 and 14 arranged in pairs at the sides of the machine at its ends, and carrying transverse beams or girders 15 and 16 respectively, which support transversely spaced stringers 17 carrying the bed forming elements 18 for the article-carrying member or travelling band.

15 The elements 18 (see Fig. 5) are preferably of channel formation and are provided with wear strips 19, and these parts are rigidly secured to their respective stringers 17.

20 The articulated travelling band or article carrying member A (see Figs. 1, 2 and 5) comprises a plurality of endless link belts or chains 20 provided with rollers 20' which bear upon the strips 19 of the bed forming elements 18, and between these chains and carried thereby are transversely disposed bearing-surface-forming members 21 of such conformation as to interlap at their adjacent edges. The members 21 are provided with opening 22 through which dirt and scale may escape, and the band is thereby made lighter and capable of readily dissipating heat.

25 As will be seen, particularly by reference to Fig. 2, the lateral edges of the band (only one of which is shown) are formed of the members 21 closely associated to provide in effect a continuous surface, whereas the intermediate portions have the members arranged in pairs at longitudinally spaced intervals.

30 The members 18 with their strips 19 are provided at the discharge end of the machine with arcuate or substantially circular return bends 23 in which the chains 20 are guided to drive sprockets 24 (Fig. 1) arranged upon a drive shaft 25 extending transversely of the machine. These drive sprockets operate upon the return flight or slack 26 of the band, same being led over idle sprockets 27 on a transverse shaft 28 back to the forward ends 29 of the members 18. Unidirectionally rotating driving means (not shown) are provided for rotating the sprockets 24 in a counterclockwise direction, as viewed in Fig. 1. The shafts 25 and 28 are mounted in suitable bearings carried by the standards 13 and 14, as shown.

35 The top or working flight 30 of the band, being supported by the rollers 20' upon the members 18, presents its bed-forming members 21 with their upper surfaces in a regulated or grid-like planar arrangement so

that the pipes or other articles fed thereto when pressed against the band and rolled over it will, of necessity, be straightened.

40 In order that the requisite pressure may be applied to the pipes or other articles as they are moved forward by the travelling band, I provide the pressure-applying member B (see Figs. 1 and 3) which comprises a plurality of grid-like surface-forming members 31 having ribs 32 between which are spaces 33 through 45 which the heat transmitted to the members 31 may be dissipated. The adjacent edges of the members 31 are provided with interlapping lugs 34, and at the two edges of the pressure-applying member, only one of 50 which is shown in Fig. 3, the surface-forming members are arranged in close relationship so as to form a continuous surface, whereas throughout the central portion they are spaced at intervals longitudinally of the 55 member.

55 As shown in Fig. 1 the surface-forming members 31 are supported with their under faces in planar arrangement by means of a carrying framework composed of beams 35 and 36 and stringers 37 extending between said beams at transverse intervals and rigidly secured thereto. Rods 38 fixed to the members 31 pass through the flanges of the stringers 37 and are fixed against downward movement relatively thereto by means of nuts 39 applied to their threaded ends. Between the lower flanges of the stringers 37 and the upper faces of the members 31 I interpose stiff helical springs 40, or other suitable resilient members, positioned by the rods 38 and serving to resiliently hold the members 31 in their desired planar arrangement and affording a means of applying a heavy yielding pressure upon the pipes or other articles operated 105 upon.

60 The framework which supports the pressure-applying member B is carried by a parallel linkage mechanism comprising similar levers 41 and 42 fixed on shafts 43 and 44 110 journaled in the standards 13 and 14 respectively, at opposite sides of the machine. These levers 41 and 42 are connected with the beams 35 and 36 by means of pivot knuckles 45 which engage with recessed blocks 46 suitably secured to the ends of the beams as by bolts and nuts indicated at 47 in Fig. 7. Also mounted on the shafts 43 and 44 at opposite sides of the machine are levers 48 and 49 (Figs. 1 and 4) arranged in parallelism and 115 connected by bars 50 provided with turn-buckles 51 whereby the parallel adjustment of the levers may be assured. The bars 50 extend through housings 52 in the standards 13 and are threaded at their ends 53 and provided with adjusting nuts 54 bearing against the housings 52. By this link and lever mechanism it will be seen that by adjustment of the nuts 54 the pressure-applying member B may be moved toward and away from the 130

travelling band A, always in parallelism therewith, to adjust the machine to articles of various diameters.

As shown, the member B is provided with an upturned leading edge b, whereby introduction of the pipes or other articles between the members A and B is facilitated.

If desired, spray heads 55 may be provided (Fig. 1) for spraying water or other cooling fluid upon the article carrying member or band A, preferably on its return flight 26.

As shown, particularly in Fig. 1, the apparatus is so arranged that the members A and B are upwardly inclined from the point at which the pipes are fed to them and this increases the desired tendency of the pipes to a rolling movement between these members.

Moreover, this inclination of the members A and B, and particularly of member B, makes this latter member suitable for water-cooling, as shown in Fig. 6. In this water-cooling arrangement, trough-like surface-forming members 56, having imperforate bottoms, are substituted for the grid-like members 31, and these members 56 have water or other cooling liquid fed to them, such liquid being fed to the highest one at the discharge end of the apparatus and flowing thence over the whole series through spill-pipes 57 until it reaches the lowest, from which it may flow to waste. Inasmuch as the discharge end of the apparatus is the cooler end, the water will gradually heat up as it nears the end at which the hot pipes are introduced, thus providing a perfect progressive cooling process upon the members 56 and the pipes in contact therewith.

The operation of the apparatus is as follows:

In the normal operation of a pipe forming machine, the formed pipes, at a high heat, as they successively leave the forming rolls 45 are projected out upon the table 1 beneath the housing 5. When a pipe is free of the forming rolls and rests bodily upon the table, it is held from rolling off of the table by the housing. When the housing is swung upwardly upon its pivot 4, the pipe will be released and will roll down the incline of the table over the bridge-piece or skid 7 and onto the articulated travelling band or article-carrying member A, and will advance there-with beneath the pressure-applying member B, its introduction between the members A and B being facilitated by the upturned leading edge b of member B, as hereinbefore indicated. The travel of member A combined with the frictional contact of member B with the pipes will cause the pipes to roll and, being hot, this rolling action will eliminate any bends or sags which form in them in the interval between their release by the forming rolls and their introduction into the straigh-

tening apparatus. Moreover, as the pipes proceed between the members A and B they will be rapidly cooled due to the heat-dissipating character of the surface-forming members 21 and 31 so that when the pipes are discharged from the machine and fall upon the cooling rack they will have become so cool as to be rigid, and any bending or injury of them on the cooling rack made highly improbable.

As previously explained, the surface-forming members 31 of the pressure-applying member B are in yielding contact with the pipes under the influence of the springs 40, and this not only provides a heavy resilient pressure upon the pipes but enables the members 31 to give somewhat when necessitated by pronounced bends and permit the pipes to roll over in spite of such bends rather than causing them to slide, as might be the case were the member B rigid.

Ordinarily, the bends and sags which form in the hot pipes occur at their ends where they protrude past the ends of the housing 5, and it is for this reason that the edge portions of the members A and B are formed with their members 21 and 31, respectively, arranged in substantially unbroken continuity, a spaced arrangement of these members 21 and 31 throughout the central portion of the members A and B being sufficient to take care of the greater portion of the length of the pipes which is usually substantially straight.

In the foregoing description I have referred to my apparatus as particularly adapted for straightening pipes, but it will be understood that it may be used for straightening other cylindrical and tubular articles. Also, various changes and modifications may be made within the spirit of the invention and the scope of the appended claims.

I claim:

1. The method of straightening cylindrical articles which comprises rolling such articles under substantially continuous pressure between a fixed member and a uni-directionally movable member.

2. The method of straightening cylindrical articles which comprises rolling such articles between a fixed member and a uni-directionally movable member having planar article-contacting surfaces.

3. The method of straightening cylindrical articles which comprises rolling such articles while in a heated condition between a fixed member and a uni-directionally movable member having planar surfaces and under pressure.

4. The method of straightening cylindrical articles which comprises rolling such articles between a uni-directionally travelling article-carrying member and a fixed pressure-applying member, to translate said articles

progressively along said article-carrying member.

5. The method of treating hot-formed metallic pipe, which comprises straightening and cooling the pipe by rolling same between planar surfaced members under substantially continuous pressure, varying in degree, in accordance with the amount of bend in said pipe.

10 6. Apparatus for straightening and cooling hot-formed metallic pipe, which comprises a travelling carrier member, a substantially stationary pressure-applying member, said members having planar pipe-contacting surfaces and serving to dissipate the heat from said pipe, and means for moving said carrier member continuously in one direction.

15 7. Apparatus for straightening cylindrical articles, comprising two substantially planar members arranged in spaced relation, and means for imparting uni-directional movement to one of said members relatively to the other, whereby an interposed article will be subjected to rolling action.

20 8. Apparatus for straightening cylindrical articles, comprising a substantially planar article-carrying member, a substantially planar pressure applying member, and means for imparting uni-directional motion to one of said members relatively to the other, whereby when an article is introduced between said members it will be subjected to a rolling action under pressure.

25 9. Apparatus for straightening cylindrical articles, comprising an article-carrying member, a pressure applying member spaced therefrom, and means for imparting uni-directional linear motion to one of said members relatively to the other, whereby when an article is introduced between said members it will be subjected to a rolling action under pressure and a continuous linear movement through the space between said members.

30 10. Apparatus for straightening cylindrical articles, comprising an article-carrying member, a pressure applying member, said members provided with planar article-contacting surfaces, and means for imparting uni-directional linear motion to one of said members relatively to the other, whereby when an article is introduced between said members it will be subjected to a rolling action under substantially continuous pressure.

35 11. Apparatus for straightening cylindrical articles, comprising a bed, an article-carrying member carried by said bed, a pressure-applying member arranged in spaced relation to said article-carrying member, and means for imparting uni-directional travelling movement to said article-carrying member relatively to said bed and to said pressure-applying member, to effect combined linear and rolling movement of an article on said

article-carrying member through the space between said pressure-applying member and said article-carrying member.

40 12. Apparatus for straightening cylindrical articles, comprising a framework carrying a bed, an article-carrying member supported by said bed, a substantially stationary pressure-applying member, means carried by said framework and resiliently supporting said pressure-applying member relatively to said article-carrying member, and means for imparting uni-directional linear movement to said article-carrying member relatively to said pressure-applying member, whereby when an article is introduced between said members it will be subjected to a rolling action under pressure.

45 13. Apparatus for straightening cylindrical articles, comprising a framework carrying a bed, an article-carrying member supported by said bed, a pressure-applying member, means including a parallel linkage carried by said framework and adjustably supporting said pressure-applying member relatively to said article-carrying member, and means for imparting linear movement to said article-carrying member relatively to said pressure-applying member, whereby when an article is introduced between said members it will be subjected to a rolling action under pressure.

50 14. Apparatus for straightening cylindrical articles, comprising an articulated travelling band having a working flight and a return flight, a bed forming a support for the working flight of said band and provided with a return bend at one of its ends, and a driving member arranged adjacent to said return bend and operatively engaging the return flight of said band to impart travelling movement thereto.

55 15. Apparatus for straightening hot-formed cylindrical articles, comprising a continuous travelling article-carrying member having a working flight and a return flight, a pressure-applying member arranged in cooperative relation to said article-carrying member, said members serving to translate said articles progressively along said article-carrying member and to roll the hot articles between them, and means for projecting a cooling fluid upon the return flight of the article-carrying member.

60 16. Apparatus for straightening cylindrical articles, comprising a travelling conveyor composed of a plurality of travelling chains and a plurality of surface-forming members carried by said chains providing a substantially planar article-carrying surface, a bed comprising members on which said chains travel and by which they are supported, means for imparting linear movement to said chains over said bed to cause the band to travel, a pressure-applying member arranged in superposition to said band and sub-

stantially fixed longitudinally thereof, said pressure-applying member including a support and a plurality of surface-forming members resiliently mounted on said support, and means for adjusting the proximity of said pressure-applying member to said band.

17. Apparatus for straightening cylindrical articles, comprising a travelling conveyor 10 composed of a plurality of travelling chains and a plurality of surface-forming members carried by said chains providing a substantially planar article-carrying surface, a bed comprising members on which said chains 15 travel and by which they are supported, means for imparting linear movement to said chains over said bed to cause the band to travel, a pressure-applying member arranged in superposition to said band, and 20 substantially fixed longitudinally thereof, said pressure-applying member including a support and a plurality of surface-forming members resiliently mounted on said support, and means for adjusting the proximity 25 of said pressure-applying member to said band, the surface-forming members of the band and of the pressure-applying member being provided with heat-dissipating means.

18. In apparatus for the manufacture of 30 hot-formed metallic pipes, the combination with the discharge mechanism of the pipe-forming machine and a cooling rack for said pipes, of apparatus for straightening said pipes comprising a travelling carrier-member and a relatively fixed pressure-applying member arranged intermediate said discharge mechanism and said cooling rack, said carrier-member adapted to receive the pipes discharged from said discharge mechanism and convey them beneath said pressure-applying mechanism, whereby the pipes are subjected to rolling under pressure to straighten them.

19. In apparatus for the manufacture of 45 hot-formed metallic pipes, the combination with the discharge mechanism of the pipe-forming machine and a cooling rack for said pipes, of apparatus for straightening said pipes comprising a travelling carrier-member and a relatively fixed pressure-applying member arranged intermediate said discharge mechanism and said cooling rack, said members provided with planar pipe-contacting surfaces, and said carrier-member 50 adapted to receive the pipes discharged from said discharge mechanism and convey them beneath said pressure-applying mechanism, whereby the pipes are subjected to rolling under pressure to straighten them.

20. In apparatus for straightening pipe, the combination with forming apparatus and cooling apparatus, of apparatus including a travelling conveyor member and a stationary pressure-applying member for conveying pipe from said forming apparatus to

said cooling apparatus, said conveyor member and pressure applying member acting to convey and simultaneously straighten said pipe.

21. The invention as set forth in claim 20, 70 wherein the conveyor member is disposed opposite the pressure applying member and its travelling movement functions to roll the pipe between said members and to convey the pipe from said forming apparatus to said 75 cooling apparatus.

In testimony whereof, I affix my signature.
WILLIAM F. CLARK.
